(57) **CLAIM**

The ornamental design for a shield for a vibrator device, as shown and described.

DESCRIPTION

FIG. 1 is a top view of a shield for a vibrator device, showing my new design.

FIG. 2 is an opposing bottom view thereof, rotated 180 degrees from that shown in FIG. 1.

FIG. 3 is a side view of the new shield for a vibrator device.

FIG. 4 is an opposing side view thereof rotated 180 degrees from that shown in FIG. 3.

FIG. 5 is a front view of the shield for a vibrator device shown in FIG. 1; and,

FIG. 6 is a back view thereof, rotated 180 degrees from that shown in FIG. 5.
